(57) **CLAIM**

The ornamental design for a bottle, as shown and described.

DESCRIPTION

FIG. 1 is a perspective view of an embodiment of a bottle according to the present design;

FIG. 2 is an exploded perspective view of the embodiment of FIG. 1;

FIG. 3 is a front elevational view of the embodiment of FIG. 1;

FIG. 4 is a left-side elevational view of the embodiment of FIG. 1;

FIG. 5 is a right-side elevational view of the embodiment of FIG. 1;

FIG. 6 is a top-plan view of the embodiment of FIG. 1;

FIG. 7 is a bottom-plan view of the embodiment of FIG. 1;

FIG. 8 is a perspective view of a second embodiment of the bottle according to the present design.

FIG. 9 is an exploded perspective view of the embodiment of FIG. 8;

FIG. 10 is a front elevational view of the embodiment of FIG. 8;

FIG. 11 is a left-side elevational view of the embodiment of FIG. 8;

FIG. 12 is a right-side elevational view of the embodiment of FIG. 8;

FIG. 13 is a top-plan view of the embodiment of FIG. 8; and, FIG. 14 is a bottom-plan view of the embodiment of FIG. 8. The broken lines are included for illustrative purposes and form no part of the claimed design. The sets of horizontal wave shaped broken lines in FIGS. 8-12 represent indeterminate claim to length.
